UNITED STATES PATENT OFFICE.

JOHN CLANCY, OF KENNER, LOUISIANA.

RAIL.

1,401,139.

Specification of Letters Patent. Patented Dec. 27, 1921.

Application filed October 15, 1920. Serial No. 417,221.

To all whom it may concern:

Be it known that I, JOHN CLANCY, a citizen of the United States, residing at Kenner, in the parish of Jefferson and State of Louisiana, have invented a new and useful Rail, of which the following is a specification.

This invention relates to railway rail joints, it being the primary object of the invention to provide a novel connection between abutting ends of rails, whereby the strain usually directed thereto, will be distributed throughout the lengths of the rails.

A further object of the invention is to provide a rail joint wherein ends will be interlocked to eliminate any possibility of lateral displacement between the sections.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 illustrates a plan view of abutting rail ends disclosing a joint constructed in accordance with the present invention.

Fig. 2 is a side elevational view of the same partly broken away.

Fig. 3 is sectional view taken on line 3—3 of Fig. 2.

Fig. 4 is a sectional view taken on line 4—4 of Fig. 2.

Fig. 5 is a sectional view taken on line 5—5 of Fig. 1.

Referring to the drawing in detail, two abutting rail sections 5 and 6 are shown, each of which comprises the usual base 7, web 8, and tread 9.

In the construction of the present rail joint, the tread portion of the rail 5 is cut at an angle at approximately 45° as indicated at 10, which cut extends through the web 8 of the rail, terminating at a point in spaced relation with the base 7 thereof, the base being however cut at right angles to the web portion thereof as at 11, there being an angularly disposed cut indicated at 12 formed on the opposite side of the base.

The end of the opposed rail section is also cut at an angle of approximately 45° in a direction opposite to the angle of the first mentioned rail section, this angular cut extending downwardly through the web portion of the rail, and terminating at a point in spaced relation with the base portion thereof, there being provided a shoulder 13 adjacent to the base 7, which shoulder is designed to accommodate the shoulder 14 formed on the opposite rail section.

The base portion of this rail section 6, on one side of the web portion thereof is cut at an angle corresponding to the angle of the base of the opposed section, while the base on the opposite side of the web portion is cut to conform to the right angled cut of the opposed section.

From the foregoing it is obvious that when adjacent rail ends cut in a manner as described, are brought together in abutting relation with each other, the sections will interlock to eliminate any possibility of lateral displacement thereof.

It might be further stated that the usual fish-plates are employed in connection with this joint for restricting movement of the abutting ends.

Having thus described the invention, what is claimed as new is:

In a scarf joint, rail sections, each of said rail sections having its base portion cut at an oblique angle, the cut portion extending from one edge of the base of the rail and terminating at a point adjacent to the web thereof, said angular cut merging into a relatively straight cut, extending from the web to the opposite edge of the rail, the tread of the rail section having a diagonal cut in a direction opposite to the oblique cut in the base, the surfaces formed by the latter diagonal cuts coöperating to prevent lateral movement of one section with respect to the adjacent section.

In testimony that I claim the foregoing as my own, I have hereto affixed my signature in the presence of two witnesses.

JOHN CLANCY.

Witnesses:

ED. STOULIG,
G. M. BECKER.
